US0D1113833S

(12) **United States Design Patent** (10) **Patent No.:** **US D1,113,833 S**
(45) **Date of Patent:** **** Feb. 17, 2026**

(54) **REMOTE CONTROL**

(71) Applicant: **Chengjun Liao**, Hsinchu (CN)

(72) Inventor: **Chengjun Liao**, Hsinchu (CN)

(**) Term: **15 Years**

(21) Appl. No.: **29/919,263**

(22) Filed: **Dec. 3, 2023**

(51) LOC (15) Cl. **14-03**

(52) U.S. Cl.

USPC **D14/218**

CLAIM

The ornamental design for a remote control, as shown and described.

DESCRIPTION

FIG. 1 is a front perspective view of a remote control, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the remote control, which form no part of the claimed design.

1 Claim, 8 Drawing Sheets
